[57] CLAIM

The ornamental design for a golf club shaft, as shown and described.

DESCRIPTION

FIG. 1 is a perspective view of a golf club shaft showing my new design;

FIG. 2 is an end view thereof, the undisclosed opposite end being identical;

FIG. 3 is an enlarged fragmented portion thereof;

FIG. 4 is a front elevational view of FIG. 1;

FIG. 5 is a front elevational view of a second embodiment of the golf club shaft as disclosed in FIG. 1; and,

FIG. 6 is a front elevational view of a third embodiment of the golf club shaft as disclosed in FIG. 1.

The broken line showing of a golf club head and handle is for illustrative purposes only and forms no part of the claimed design.
